UNITED STATES PATENT OFFICE.

FRANCIS A. MCKEE, OF BELTON, TEXAS.

SEED-PLANTER.

SPECIFICATION forming part of Letters Patent No. 556,551, dated March 17, 1896.

Application filed October 15, 1895. Serial No. 565,785. (No model.)

To all whom it may concern:

Be it known that I, FRANCIS A. MCKEE, a citizen of the United States, residing at Belton, in the county of Bell and State of Texas, have 5 invented certain new and useful Improvements in Seed-Planters; and I do declare the following to be a full, clear, and exact description of the invention, such as will enable others skilled in the art to which it appertains to 10 make and use the same.

My invention relates to improvements in walking seed-planters; and it consists in the peculiar and advantageous construction, novel combination and adaptation of parts 15 hereinafter described, and distinctly pointed out in the claim appended.

In the accompanying drawings, Figure 1 is a side elevation of my improved planter. Fig. 2 is an enlarged horizontal section taken in the plane indicated by the line $x-x$ of Fig. 1. Figs. 3 and 4 are sections taken in the planes indicated by the lines $y-y$ and $z-z$, respectively, of Fig. 2. Fig. 5 is a detail perspective view hereinafter referred to. Fig. 6 is a detail section taken in the plane indicated by the line $w-w$ of Fig. 5, and Fig. 7 is a detail perspective view of the ejector-wheel.

Referring by letter to said drawings, A indicates the body portion of my improved 30 planter, which may comprise suitable side bars a , a cross-bar b , and the horizontal plate c , having the central opening d and the seed-opening e , surrounded by the depending nipple f .

B indicates the beam, which is by preference formed by the two members g , which are fixedly connected to opposite sides of the body A, and are brought and suitably connected together in advance of said body and are designed at their forward end for the connection of a draft-animal, and C indicates the standard, which carries a suitable shovel-plow h at its lower end and has its upper end bifurcated, so as to form the branches i , which 45 are pivotally connected to opposite sides of the body A, for a purpose presently described. This standard C has a strap D pivotally connected to it, and this strap is provided with a plurality of apertures j at its upper end, so 50 as to permit of its being adjustably connected by the bolt k to the beam B to hold the stand-

ard C at various angles of inclination to the body and regulate the depth of the plow-furrow. Said standard C is furthermore provided with a fixedly-connected arm E, which 55 extends rearwardly from it and is provided at such rear end with an eye m , as shown. This arm E is designed to receive and hold the seed-spout F, which is preferably formed of leather and has its upper end suitably connected and surrounding the nipple f and its lower end arranged immediately in rear and partly beneath the shovel-plow, so that the deposited seed will be covered by the earth raised by the plow. It follows from this that 60 the seed-spout F will be moved with the shank C and will be adjustably fixed when said shank is adjustably fixed in the manner before described.

G indicates the handles of the planter, which 70 are connected with the beam B, preferably by the transverse bolt k , and extend rearwardly and upwardly on opposite sides of the seed-hopper, presently described, and are fixedly connected to bars n rising from the body 75 A, and H indicates the rearwardly-extending frame, which is loosely connected at its forward end to the transverse shaft I, journaled in the body A. This frame H carries at its rear end the rotary shaft J, on which the 80 traveling wheel K and the sprocket-wheel L are fixed, as shown in Fig. 1 of the drawings. The said sprocket-wheel L is connected by a chain M with a sprocket-wheel N on the transverse shaft I, and in consequence of this it 85 will be observed that when the planter is in motion and the wheel K is rotated such movement will be transmitted to the shaft I to serve a purpose hereinafter pointed out.

In order to transmit motion from shaft L 90 to shaft I through the medium of the chain M, it is necessary to keep said chain taut, and to accomplish this end, as well as to regulate the chain to suit the different adjustments of the shank C, I provide the idler-wheel P, which engages the chain M, and is adjustably connected with the frame H, preferably in the manner shown in Fig. 1.

Arranged in the opening d of the body plate c and loosely mounted on a bolt p and secured thereon, preferably by a nut, as 100 shown, is a beveled gear-wheel q , which

meshes with a beveled gear-wheel r (see Fig. 3) on the shaft I , from which it gains its movement. This beveled gear q is provided with one or more upwardly-extending projections 5 s , which are arranged off its center and are designed to take into correspondingly-arranged apertures in the rotary seed-plate Q , so as to fix said plate, which is also loosely mounted on the bolt p , to said gear-wheel q .
 10 The said seed-plate Q is provided with the usual circular series of apertures t , and it is held down in position and in engagement with the gear-wheel q by the casting R , (better illustrated in Fig. 5,) which is mounted on the bolt p , as shown. This casting R is provided with the ears u for the passage of screws which connect it to the body-plate c , and at its rear end it is provided with an ear v , through which passes the thumb-screw w ,
 15 which is provided to facilitate the removal of the casting, for a purpose presently described. Said casting has the seed-hopper S suitably connected to or formed integral with it, and it is provided with the openings x adjacent to its edge to permit the seed to pass down into the openings t of the seed-plate, and is furthermore provided with the pivoted spring-pressed block y , designed to even off the seed in the aperture t of plate Q , and
 20 with the piece z , which rests above the block y and between which and said block the spring a' is interposed, as shown.

A' indicates an ejector-wheel which is carried by a strap B' , pivotally connected to the hopper S , (see Fig. 2,) and is arranged above the seed-opening e in the body-plate so as to force the seed out of the apertures t in the plate Q when they come above said opening e .

In using my improved planter a draft-animal is hitched to the beam B , and the planter with seed in its hopper S is driven along the line that it is designed to plant the seed, the driver walking behind and grasping the handles, so as to assist in keeping the plow in 40 the ground. With such a planter it will be readily observed that a large amount of seed along desired lines may be planted by a single draft and one man in a short space of time.

As will be understood from the foregoing 50 description, the plate Q and the casting R are readily removable, and when desired said plate Q may be readily removed to give place to a plate having different size and differently-arranged openings t . Indeed I contemplate 55 plate in practice furnishing a plurality of plates Q with each planter, said plates being designed for planting thick and thin and for large and small seed. I also contemplate providing two seed boxes or hoppers with each 60 machine, one being designed for cotton-seed and the other for corn and other smaller seed.

It will be further observed that when desired the seed-plate, casting R , and hopper or seed-box S may be readily removed and the 65 machine used simply as a cultivator.

It will further be observed that when de-

sired draft-animals may be hitched to two planters, and they may be arranged side by side, so as to enable a single workman to operate them.

In order that the planter may be readily turned at the end of a row, I provide the hook T , which is loosely connected with the handles G and is designed to be hooked into the wheel K , so as to enable the operator to raise 75 said wheel with the handles and thereby readily lift the planter around.

For the purpose of facilitating the movement of the planter from one place to another I provide the link W , which, when not in use, 80 may be carried upon one of the handles, as shown. This link W has hooks at its ends, and such hooks are designed to be placed in engagement with the upper end of the strap D and the hanger which carries the idler-wheel P , so as to hold the plow above the ground and enable the planter to rest entirely 85 upon the wheel K . In placing the link W in engagement one of its ends is hooked under the upper portion of strap D above the beam 90 B . The handles G are then lifted and the wheel K is permitted to assume a position below the body A , when the other end of the link W is hooked over the hanger-carrying wheel P . When this is done, it will be seen 95 that when the operator bears on the handles G the plow will be lifted from the ground. This, as will be readily observed, will permit of the planter being readily removed from one field to another.

Having described my invention, what I claim is—

The seed-planter described comprising the body having the seed-discharge opening e , and also having the opening d , the transverse shaft I , journaled in the body and having a gear-wheel r , the rotary seed-plate having apertures t , adapted to register with the opening e , and also having one or more apertures off its center, the central vertical bolt p , carrying said seed-plate and having its lower end threaded and provided with a nut, the gear-wheel loosely mounted on said bolt and arranged in the opening d , and meshing with the gear-wheel r , and having one or more 105 projections s , engaging the apertures in the seed-plate, the casting R , receiving the bolt p , the screw detachably connecting the casting R and the body, the hopper or seed-box connected to the casting R , the block y , pivotally connected to the casting R , and arranged above the seed-plate in the path of the seed-apertures therein and having a recess in its upper side, the piece z , connected to the casting R , and arranged above the block 110 y , the coiled spring arranged in the recess of block y , and interposed between said block and the piece z , a strip pivotally connected to the hopper or seed-box and carrying a wheel 115 extending through the casting R , and adapted to enter the apertures in the seed-plate, the frame H , loosely connected to the trans-

verse shaft I, and extending rearwardly therefrom, the shaft J, journaled in said frame adjacent to its rear end and carrying a fixed traveling wheel, sprocket-wheels fixed on the 5 shafts I, and J, and a sprocket-chain connecting the same, all substantially as and for the purpose set forth.

In testimony whereof I affix my signature in presence of two witnesses.

FRANCIS A. MCKEE.
